UNITED STATES PATENT OFFICE

CHARLES J. DAHLGREN, OF EAST ORANGE, NEW JERSEY

BUCKLE

Application filed July 30, 1928. Serial No. 296,326.

This invention relates to buckles, and particularly, to the type shown and described in my prior patents for buckles, Nos. 1,666,528 and 1,666,529, dated April 17th, 1928, to which reference is made. I have found that while the buckles which I have shown in my prior patents are efficient and operate perfectly on straps which are made of comparatively thick cloth, there is some likelihood of the buckle slipping when applied to comparatively thin and fragile cloths such as silks and the like. I have also found that sharp points on the buckle tongues are apt to prick and injure the fingers of the user, and may penetrate or injure the cloth.

This invention contemplates the provision of a buckle wherein straps, even though made of thin material, may be securely held in the closed position of the buckle against displacement, and wherein the buckle tongues are highly effective to hold the strap or belt even though the points thereof are not sharp. The various objects of my invention will be clear from the description which follows, and from the drawings, in which,

Fig. 1 is a top plan view of my improved buckle.

Fig. 2 is a vertical section of the same, taken on the line 2—2 of Fig. 1.

Fig. 3 is a vertical section of the same, taken on the line 3—3 of Fig. 1.

Fig. 4 is a front view of the buckle shown in Fig. 1.

Fig. 5 is a vertical section of a modified form of my improved buckle wherein the stop ledge for the tongues is continuous with the slotted wall of the buckle and the downwardly turned bracing and finishing member shown in Figs. 1, 3 and 4, is employed.

Fig. 6 is a view of another modified form of the buckle shown in Fig. 5, excepting that the downwardly turned bracing member is omitted, and Fig. 7 is a top view of part of a buckle, showing how indentations may be used instead of slots in the wall.

Fig. 8 is a combined top view and horizontal section, taken on the line 8—8 of Fig. 3, showing how the strap is forced by the tongues into the slots and thereby waved for firmly holding the strap in position.

In the practical embodiment of my invention, I prefer to provide a frame 10, preferably formed of a single piece of sheet material in which a central opening 11 is made. The frame consists of the rear cross bar 12, 55 the front cross bar 13 and may include the downwardly curved bracing and finishing member 14 continuous and integral with the cross bar 13. Said member 14 is preferably of the full width of the bar 13 at its upper 60 edge, though it may taper to less width at its lower extremity 22. The upper face of the entire frame 10 preferably lies in a horizontal plane though there may be a slight variation in the heights of the parts due to the 65 slight distortion of the material when the sides of the frame are bent. The sides 15 are bent downwardly at substantially right angles to the plane of the upper face of the frame and are perforated as at 16 for the reception of the projecting lugs 17 of the swinging tongue frame 18.

Continuous with the inner edge 19 of the front bar 13 of the frame and bent downwardly therefrom is the substantially vertical wall 20, in which a series of indentations or spaced slots as 21 are made. Said indentations or slots terminate just below the inner edge 19 so that the slots are substantially invisible in the operative position of the buckle, 80 and will be referred to hereinafter as "slots". It will be understood that the indentations or slots 21 in the vertical wall 20 may be entirely dispensed with, if desired, dependence being had in that case on the cooperation of 85 the tongues 27 with the inner face of the wall 20 for securing the strap in place. It will further be understood that in place of the slots 21 illustrated in Figs. 1, 2, and 8 as passing completely through the wall 20, a 90 series of grooves or indentations of various shapes adapted to receive the points 28 of the tongues 27 may be provided as may be found convenient or desirable and as indicated in one form in Fig. 7.

The entire buckle frame 10 being formed from a single piece of sheet material in which a central opening 11 is made, as has been hereinbefore pointed out, the wall 20 may readily be formed integral with the front cross 95

bar 13 by utilizing the front portion of the material arranged in the opening 11 and bending said material relatively to the front end 13 as will be obvious to those skilled in the art.

5 In the modification shown in Figs. 1 to 4 inclusive, the lowermost portion 22 of the finishing and bracing member 14 extends inwardly past the bottom edge 23 of the upright wall 20 so as to form a stop for limiting the movement of the tongue frame 18, as will soon be described. It will be noted that the member 14 serves to brace the bar 13 of the frame and to finish said end, and that in the 10 modification now being described, said member also serves as the stop for the tongue frame. Said frame has a substantially rectangular opening 24 therein, dividing the frame into the rear cross bar 25 and the front tongue bar 26. On the tongue bar, I prefer to form a series of forwardly projecting tongues as 27, terminating in dulled or rounded points 28 which are arranged in alignment with the respective slots 21 and do not penetrate the cloth nor otherwise injure it, and which results in a safety buckle wherein pricking of the fingers in handling is avoided. Said tongue frame 18 is also formed preferably of a single piece of sheet material, the 15 lugs 17 thereof being preferably arranged in alignment with the cross bar 25.

It will be understood that one end 32 of the belt or strap 29 is passed under the rear bar 12 of the frame and over and about the cross bar 25 of the tongue frame, being secured in place by suitable means such as the stitching 30. The other end 31 of the belt or strap is passed upwardly through the frame, past the edge 22 of the member 14 into engagement 20 with the tongues 27. As the tongue frame 18 is now pressed downwardly, it pivots about the lugs 17 without disturbing the secured end 32 of the belt. At this time, the points 28 of the tongues 27 just clear the inner edge 15 19 of the front frame end 13, forcing the material of the belt past said edge and into the slots 21 (Fig. 7). Further movement of the tongue frame 18 forces the material into the slots 21 for a greater distance, due to the fact 25 that the center of rotation of the tongue frame is below the edge 19. The movement of the tongue frame may be thus continued until brought to a stop against the stop portion 22 of the member 14. In this position, 30 the material has been waved transversely under tension, since it is forced by the points 28 into the center of the slot and emerges from the slot to contact the outside edges thereof. The material is further folded or creased into 35 a reversed fold as indicated in Fig. 3, whereby the belt end 31 is firmly held in place against displacement no matter how thin or fragile the material may be. It will be understood that the tension put on the strap at the place where it is held by the tongues and

tends to compress the tongue frame to a sufficient extent to resist raising of said frame and consequent slipping of the buckle.

70 Referring now to Fig. 5, I have there shown a modification wherein the wall 20 is continued past the member 14 and terminates in a substantially horizontal stop portion 33 against which the tongues 27 may come to rest. In this modification, the member 14 terminates at an edge as 34 adjacent to or in contact with the front face of the wall 20.

75 If desired, the member 14 may be entirely omitted, as shown in Fig. 6 though the operation of my improved buckle is precisely the same as that hereinbefore described.

80 It will be seen that I have provided a simple and efficient buckle, well designed to meet the severe requirements of practical use and adapted to receive and to hold comparatively thin material, while designed to prevent injury to the material and to the fingers. It will further be seen that, by the provision of the indentations or slots in a depending wall of said buckle and by proportioning the tongues 27 so that said tongues may partly enter the indentations or slots and force material thereinto to a greater or lesser extent, it becomes possible to firmly grip a strip of material no matter how thin and to hold it against undesired displacement in the buckle.

85 While I have shown and described preferred embodiments of my invention, I do not wish to be understood as limiting myself to the precise construction shown and described but intend to claim my invention as broadly as may be permitted by the state of the prior art and the terms of the appended claims.

90 I claim:

1. In a buckle, a buckle frame including a front bar, the upper face of which lies substantially in the plane of the remainder of the upper surface of the frame, a tongue frame pivoted to the frame at the sides thereof, a substantially upright wall depending from and integral with the inner edge of said front bar, tongues on said tongue frame lying entirely within the buckle frame for cooperating with said wall to clamp the material of a strap therebetween in the operative position of the buckle and means integral with the front bar and extending downwardly therefrom for limiting the lowermost position of the tongue frame.

105 2. In a buckle, a buckle frame of a single piece of sheet material comprising a rear frame bar, depending sides, and a front frame bar, said front bar having a substantially upright wall depending from the inner edge thereof, and said wall having spaced slots 110 therein, a tongue frame swingable in said depending sides, and tongues projecting from the tongue frame and spaced apart to correspond with said slots for clearing the inner edge of the front frame bar on the swinging

of said tongues and forcing the material of a strap into said slots.

3. In a buckle, a frame having a front bar element, a wall element arranged at substantially right angles to said bar element and of substantially the same height as said frame and continuous with the inner edge of said bar element, a tongue-carrying member pivotally mounted in said frame, tongues projecting from said member and adapted to just clear said inner edge, and a stop ledge integral with one of said elements and projecting inwardly past the lower edge of said wall element for limiting the lowermost position of the tongues.

4. In a buckle, a frame having side bars, a front bar connecting the side bars, a wall having spaced slots therein arranged at substantially right angles to said front bar, and continuous with the inner edge of said front bar, a tongue-carrying member pivotally mounted in said side bars, and tongues projecting from said member and adapted to just clear said inner edge, the centers of said tongues being aligned with the center lines of the respective slots.

5. In a buckle, a frame having a front bar, a slotted wall depending from the inner edge of said front bar, a swingable tongue-carrying member mounted in said frame, tongues on said member adapted to force material of a strap into the slots of the wall, said slots terminating below the upper face of the frame and being invisible from the top.

6. In a buckle, a frame having a front end thereon substantially triangular in cross section, said front end including a flat front bar, an unmutilated straight line inner edge on said front bar, and including a member having spaced slots therein terminating below said bar, and means on the frame for gripping a strap by forcing said strap into the slots, waving the strap transversely and forming transverse folds in the strap.

7. In a buckle, a buckle frame of a single piece of sheet material including an unmutilated front bar, a wall depending from the inner edge of said bar and having spaced slots therein, said slots terminating below said bar and being invisible from the top of the frame, a tongue frame of a single piece of sheet material pivoted to the buckle frame, dull-pointed tongues projecting forwardly of the tongue frame and arranged in alignment with the slots, and a stop ledge for the tongues integral with the bar and projecting past the lower edge of said wall, said tongues cooperating with the upright edges of the slots and with the inner edge of said bar for folding and waving the material of the strap held by said buckle transversely, and being of such length as to just clear the said inner edge on the swinging of the tongue frame.

8. In a buckle, a buckle frame, having a

front end of substantially triangular cross-section, a member pivoted to the frame, tongues on said member, said front end including a flat front bar, and including a wall integral with and depending from said bar and adapted to cooperate with the tongues, for clamping material therebetween, said wall lying in a plane at substantially right angles to that of the upper face of the frame.

9. In a buckle, a buckle frame having perforated depending sides, a front bar on the frame connecting said sides, a substantially upright wall depending from said bar and integral therewith, a tongue-carrying member, lugs on said member passed through the perforations of said sides for swingably supporting the member, and tongues on said member for forcing material of a strap toward said wall.

10. In a buckle, a frame of a single piece of sheet material including a rear cross bar, a front bar lying substantially in the same plane as said rear cross bar, perforated depending sides joining said rear cross bar and said front bar, said frame having an inner pending sides joining said rear cross bar and the front bar, a wall integral with and of less length than said front bar and depending from the inner edge thereof and bent from that portion of the piece of sheet material lying at the front end of said opening and adjacent the front bar of the frame, a tongue carrying member, lugs on said member inserted into the perforations of the depending sides and swingably supported thereby in said frame, and tongues projecting from the front end of said member and arranged to just clear the inner edge of the front bar whereby material arranged between the tongues and said wall is compressed therebetween, and the tongues penetrate partway into said material.
